CRANK CASE HEATER

Don H. Bushnell, Washington, D. C.

Application May 3, 1934, Serial No. 723,783

10 Claims. (Cl. 219—38)

This invention relates to a sludge remover and more particularly to a method and means for removing sludge from the crank-case of an automobile or the like.

5 An object of the invention is to provide a new method for quickly and effectively removing the sludge that accumulates in the crank-case. A further object is to apply a relatively high heat to specific points of a crank-case to produce an 10 effect upon the oil whereby the removal of sludge therein and in the case is effected. Other specific objects and advantages will appear as the specification proceeds.

The invention is illustrated, in a preferred embodiment, by the accompanying drawings, in 15 which—

Figure 1 is a perspective view of apparatus embodying my invention; Fig. 2, an enlarged broken sectional view, the section being taken as indicated at line 2 of Fig. 1; Fig. 3, a transverse sectional view, the section being taken as indicated at line 3 of Fig. 2; Fig. 4, a broken view in elevation showing the heating mechanism applied to the crank-case of an automobile; Fig. 5, a broken 25 bottom plan view of a portion of the supporting frame; Fig. 6, a sectional view of the spring arm, the section being taken as indicated at line 6 of Fig. 5; Fig. 7, a longitudinal sectional view of the heating element, the section being taken as indicated 30 at line 7 of Fig. 1; and Fig. 8, a broken sectional view, the section being taken as indicated at line 8 of Fig. 7.

Various devices have been developed for heating the crank-case of an automobile so as to 35 warm the lubricating oil therein. Such warming of the lubricant results in making it easier for the motor to start and ensures better circulation of the lubricant during the warming up of the motor. The apparatus which I have designed 40 is for the purpose of supplying intense heat at specific points of the crank-case so as to produce a motion in the oil approaching turbulence which stirs up, dissolves and sets in motion the thick accumulation of sludge composed of foreign particles and solidified oil components that adhere 45 to the bottom and lower side walls of the crank-case. The drain plug of the crank-case is usually at or near the center of the crank-case bottom and in order to effectively remove the sludge, I have provided means for supporting heating elements at opposite ends of the crank-case so that the heated oil from the ends of the case 50 flows down to the outlet, as the crank-case is drained, thus completely cleansing the lowest portion of the crank-case, which is the point

where most sludge collects. At the same time, the crank-case is not unduly heated because of the layer of sludge insulation which is thickest near the center of the case. In order to support the heating elements at the desired points, it is 5 necessary that the supporting apparatus be adjustable and extensible so as to adapt it for crank-cases of different sizes and shapes.

In the illustration given, I provide tubular end pieces 10 at the four corners of the rectangular frame and connect the members 10 by the reduced cylindrical members 11 which are received within sleeves or tubes 10. The sleeves 10 may be of any suitable construction. In the illustration given, each comprises a sleeve member 12 which is connected to a tubular elbow 13. The elbow is provided with an enlarged ring end 14 receiving and soldering to the sleeve end 10. At its opposite end, each of the elbows is provided with an enlarged end 15 receiving a cylindrical 20 bar 16 which is fixed to the ends 15 by means of pins 17. A T-shaped tubular member 18 receives the fixed pin 17 so as to rotate freely thereon. The member 15 is provided with a tube 19 extending at right angles to the main body of the 25 member 18 and receiving the heating element support 20. As shown more clearly in Figs. 2 and 3, tube 19 is provided with a set screw 21 which engages a groove 22 in the support 20. The extent of rotation of the part 20 is thus limited. 30

Each of the supports 20 carries a heating element 23 which may be of any suitable construction sufficient to supply a relatively high heat to a specific point of the crank-case. As shown more clearly in Fig. 7, the heating element 23 35 comprises a metal casing 24 affording top and side walls and a bottom wall 25 closing the casing 24. The electric resistance heating element 26 is supported in the upper portion of the casing between mica layers 27, the element being 40 laced through the lower layer. Below the element 26 is a block of asbestos 28 and below the block 28 is sheet asbestos 29. The lower wall 25 and the asbestos layers 28 and 29 are apertured 45 to receive terminals 30 and 31 which are connected by straps 32 and 33 with the heating element 26. Depending from terminals 30 and 31 are socket shanks 34 and 35 which are adapted 50 to enter the socket of the connecting plug. The heating element itself, in operation, preferably reaches a temperature of about 600° F.

Any suitable means may be provided for supporting the frame and the heating element against the crank-case. The means may consist of lifting mechanism resting on the floor of the 55

garage and which may be actuated to raise the frame to the bottom of the crank-case. If desired, means may be employed for suspending the frame from projections or flanges present on the 5 crank-case. In the illustration given, spring arms are employed which, in turn, are equipped with hooks adapted to engage the flanges 36 of the case. Mounted on each of the cylindrical members 11 is a sleeve 37 which is freely rotatable 10 thereon. Secured to the sleeve is a connecting shank 38 imbedded in a union 39. The union 39 is drilled to receive a tube 40 having a closed upper end 41. The closure 41 is perforated to receive a hook arm 42. The arm 42 or shank within 15 the tube 40 is encircled by a spring 43 and the lower end of shank 42 is equipped with a head 44 adapted to engage the bottom of the spring and to compress it as the shank is drawn upwardly. The upper end of the shank 42 is bent to 20 provide a hook 45.

To limit the extension of the slidable sleeves 12, I provide the sleeves on their bottom sides, as shown in Fig. 5, with slots 46 which are engaged by screws 47 secured to the cylindrical 25 members 11.

In the operation of the apparatus illustrated, the sleeves 12 are adjusted on the cylindrical frame members 11 so as to bring the heating elements 23 directly below the end portions of the 30 crank-case. The elements 23 are swung into a position whereby they fit the contour of the crank-case bottom. If there are projections or irregularities in the bottom wall of the crank-case, the elements can be swung into such a 35 position as to fit between projections and rest against the bottom wall of the case. The hooks 45 are then drawn upwardly to engage the flanges 36. The rotatable sleeve 37 and the construction of the spring arm permits the hooks to be adjusted to engage various types of flanges or projections on the crank-case. The plugs are then connected to the elements 34 and 35 so that a current flows through the heating elements 26. A 40 quick intense heat is developed which raises the temperature of the oil in the crank-case above the heating elements to such a degree that turbulence sets in. The motion of the oil and its temperature which is preferably kept below 300° F., loosens and dissolves the sludge bodies and reduces 45 them to a liquid condition. After a short while, the drain plug is removed and the heated oil flows to the lower central portion of the crank-case tending to dislodge and remove also the sludge that lies there. The tubular frame permits the oil to drain freely from the drain and between the elements of the frame. After the 50 sludge has been removed from the crank-case, the apparatus may be readily removed by withdrawing the hooks 45 from engagement with flanges 36. If desired, a flushing oil may then be introduced and circulated through the lubricant conduits and then allowed to drain off. Fresh lubricant is supplied to the crank-case 55 after the removal of the sludge.

While I have described specific mechanism which is adapted to effect the purpose above described, it will be obvious that many changes may be made in the method of supporting the frame and in the specific construction of the frame and heating elements themselves, without departing 60 from the spirit of my invention.

The foregoing detailed description has been given for clearness of understanding only, and no unnecessary limitations should be understood 65 therefrom, but the appended claims should be 70

construed as broadly as permissible, in view of the prior art.

I claim:

1. In a device of the character set forth adapted for use with the crank-case of an internal combustion motor, a frame, spaced electric resistance elements adjustably supported by the frame and movable toward and away from each other, means for supporting said frame adjacent the bottom of the crank-case, said frame being provided with means for adjustably supporting the heating elements to fit the contour of the crank-case ends, and means for supplying an electric current to said heating elements. 10

2. In a device of the character set forth adapted for use with the crank-case of an internal combustion motor, a tubular extensible frame, spaced electric resistance heating elements adjustably supported by the ends of said frame, means for supporting said frame adjacent the bottom of the 20 crank-case, and means for supplying an electric current to said heating elements. 15

3. In a device of the character set forth, a rectangular tubular frame, sleeves mounted on the ends of said frame and rotatable thereon, a support carried by each of said sleeves, an electric resistance heating element carried by each of said supports and rotatable thereon, and means for supplying electric current to said heating elements. 25

4. In apparatus of the character set forth, an extensible tubular frame, means limiting the extension of said frame, electric resistance heating elements supported at the ends of said frame, and means for supplying an electric current to said heating elements. 30 35

5. In apparatus of the character set forth, a frame, heating elements adjustably supported at the ends of the frame, and spring arms rotatably mounted on said frame near its center and 40 equipped with means for engaging projections on a crank-case to support said heating elements near the opposite ends of the crank-case. 45

6. In apparatus of the character set forth adapted for use with the crank-case of an internal combustion motor, a rectangular extensible frame, electric resistance heating elements carried by the ends of the frame, electric terminals on each of said heating elements, means for supplying current directly to each of said terminals, and spring supporting arms rotatably mounted 50 on a central portion of the frame and having ends adapted to engage projections on said crank-case. 55

7. In apparatus of the character set forth, spaced electric resistance heating elements, telescoping frame elements supporting said heating elements and extensible to support said elements adjacent the end portions of a crank-case, spring hook members engaging the central portion of 60 said frame and adapted to engage projections on said crank-case to support said heating elements thereagainst, and means for supplying electric current to said resistance elements. 65

8. Sludge-removing apparatus comprising: a tubular frame, rotatable sleeve members carried by the ends of said frame, support posts carried by said sleeves, heating elements substantially the width of the frame and carried by said posts, sleeves carried by said frame adjacent its central longitudinal sides, and extensible spring hooks carried by said sleeves and adapted to engage projections on a crank-case. 70

9. Sludge-dissolving apparatus adapted for use with the crank-case of an internal combustion 75

motor comprising: a substantially rectangular tubular frame, heating elements supported by the ends of the frame and adapted to supply heat sufficient to raise the temperature of the oil within the crank-case to substantially 300° F., rotatable sleeves engaging the central portions of the longitudinal sides of the frame, and extensible spring hooks carried by said sleeves and adapted to engage projections on said crank-case.

10. In apparatus of the character set forth

adapted for use with the crank-case of an internal combustion motor, a frame, spaced electric resistance elements, supports for said electric resistance elements adjustably carried by the frame for movement toward and away from each other, means for supporting said frame adjacent the bottom of the crank-case, and means for supplying an electric current to said heating elements.

DON H. BUSHNELL. 10
